DESIGN FOR A COMBINATION COMB AND MANICURING IMPLEMENT

Hamell J. Suhadolc, Hoboken, N. J.

Application February 24, 1938, Serial No. 75,391

Term of patent 7 years

To all whom it may concern:

Be it known that I, Hamell J. Suhadolc, a citizen of the United States and a resident of Hoboken, county of Hudson, State of New Jersey, have invented a new, original, and ornamental Design for a Combination Comb and Manicuring Implement, of which the following is a specification, reference being had to the accompanying drawing, forming part thereof, and in which,

Fig. 1 is a side elevational view of a combination comb and manicuring implement showing my new design;

Fig. 2 is a top plan view; and
Fig. 3 is an end elevational view thereof.

The characteristic feature of applicant's design resides in the ornamented portions over the teeth on the side of the comb.

I claim:

The ornamental design for a combination comb and manicuring implement, as shown and described.

HAMELL J. SUHADOLC.
